CLAIM

The ornamental design for the casual shoe with pocket, as shown and described.

DESCRIPTION

FIG. 1 is a left side elevational view of a casual shoe with pocket showing my new design; the right side being similar but without the pocket;

FIG. 2 is a top plan view thereof;

FIG. 3 is a bottom plan view thereof;

FIG. 4 is a left side elevational view of a second embodiment of my new design of FIGS. 1-3, the right side being similar but without the pocket;

FIG. 5 is a top plan view of FIG. 4, the bottom plan view being identical to FIG. 3;

FIG. 6 is a left side elevational view of a third embodiment of my new design of FIGS. 1-3, the right side being similar but without the pocket, and the bottom plan view being identical to FIG. 3;

FIG. 7 is a left side elevational view of a fourth embodiment of my new design of FIGS. 1-3, the right side being similar but without the pocket;

FIG. 8 is a top plan view of FIG. 7, the bottom plan view being identical to FIG. 3;

FIG. 9 is a left side elevational view of a fifth embodiment of my new design of FIGS. 1-3, the right side being similar but without the pocket;

FIG. 10 is a top plan view of FIG. 9, the bottom plan view being identical to FIG. 3;

FIG. 11 is a left side elevational view of a sixth embodiment of my new design of FIGS. 1-3, the right side being similar but without the pocket, and the bottom plan view being identical with FIG. 3;

FIG. 12 is a left side elevational view of a seventh embodiment of my new design of FIGS. 1-3, the right side being similar but without the pocket, and the bottom plan view being identical with FIG. 3;

FIG. 13 is a left side elevational view of an eighth embodiment of my new design of FIGS. 1-3, the right side being similar, but without the pocket, and the bottom plan view being identical to FIG. 3; and

FIG. 14 is a left side elevational view of a ninth embodiment of my new design of FIGS. 1-3, the right side being similar, but without the pocket, and the bottom plan view being identical with FIG. 3.
